UNITED STATES PATENT OFFICE

1,933,532

ELECTRICAL FURNACE

John T. Nichols, Pittsburgh, Pa., assignor to
 American Sheet and Tin Plate Company, a corporation of New Jersey

Application October 7, 1932. Serial No. 636,736

3 Claims. (Cl. 13—25)

This invention relates to electrical furnaces heated by resistance bars mounted by terminal bars arranged in holes in the furnace structure, one of the objects being to prevent the passage of gases around these terminal bars.

It is necessary to renew such heating resistance bars when they become disabled through use or accident and, as this necessitates the removal of the terminal bar, it is necessary that the invention effect such sealing by a readily removable means, this being a second object. Other objects than the above may be inferred from the following illustrative example of the invention.

Referring to the drawing:

Figure 1 is a vertical cross-section of a furnace portion.

Figure 2 is an end elevation.

Figure 3 is an enlargement from Figure 1.

No attempt has been made to illustrate a complete furnace, it being deemed sufficient to show only its wall 1, a terminal hole 2, the terminal bar 3 and the end of a heating resistance bar 4. The terminal bar 3 engages and mounts the resistance bar 4 and has an externally projecting 25 shouldered end 3^a. The end 3^a is engaged by current conducting mechanism in the conventional manner. The terminal bar itself is of the usual water cooled variety fitting loosely in the hole, and the entire assembly as so far described 30 is well known to any one familiar with these furnaces.

The resistance bar 4 expands and contracts when its temperature changes and moves the terminal bar accordingly. Any means which is 35 to seal the space between the terminal bar 3 and the hole in the furnace wall must be sufficiently flexible to accommodate this movement.

According to the present invention a metallic 40 bellows 5 encircles the projecting end of the terminal bar 3. This bellows is provided with an affixed inwardly extending end 6 which fits snugly around the terminal bar and engages the shoulder of its end 3^a. Here it is held by a nut 7 which is screw-threaded onto the terminal bar, so as to 45 clamp it thereagainst. Preferably, this nut is provided with radial grooves 7^a for engagement by a suitably constructed wrench.

The other end of the bellows 5 is mounted by a refractory and insulating ring 8 which extends 50 outwardly a sufficient distance to engage the outside of the furnace's wall 1 around the hole 2. This ring may be of asbestos and is clamped to the wall's outside by an annular mounting member 9. Preferably this is effected by extending 55 screws 10 which pass through open ended slots

11 and are provided with wing-nuts 12. The open ended slots 11 permit the quick removal of the member by partial rotation without requiring the removal of the wing-nuts.

The above construction effectively prevents the 60 escape of gas through the hole 2 around the terminal bar 3 and at the same time provides the requisite flexibility. Should the terminal bar 4 need replacement the wing-nuts 12 are loosened, the annular member 9 given a slight rotation and the terminal bar removed. The end 3^a of the terminal bar is screw-threaded in place and its removal permits the disengagement of the bellows 5.

While I have shown and described one specific 70 embodiment of my invention it will be understood that I do not wish to be limited thereto, since various modifications may be made without departing from the scope of the invention as defined in the appended claims. 75

I claim:

1. An electrical heating furnace including the combination of a wall having a hole therein, a heating resistance bar arranged in said furnace with its end registering with said hole, a terminal bar arranged in said hole to engage the end of said resistance bar and with an externally projecting shouldered end, a bellows encircling the projecting end of said terminal bar and having an inwardly extending end which fits the 80 bar's shouldered end, a nut arranged in screw-threaded engagement with said bar and clamping the inwardly extending end of said bellows to the shouldered end of the bar, and means for fixing the other end of said bellows to the outside 85 of said wall in a gas-tight manner.

2. An electrical furnace including the combination of a wall having a hole therein, a heating resistance bar arranged in said furnace with an end registering with said hole, a terminal bar 90 arranged in said hole to engage the end of said resistance bar and having an externally projecting shouldered end, a bellows having an inwardly extending end fitting the shouldered end of said terminal bar, an annular insulating ring mounting the other end of said bellows and having a diameter permitting it to engage the portions 95 of said wall adjacent said hole, means for clamping the inwardly extending end of said bellows against the shouldered end of said terminal bar, and removable means for clamping said annular insulating ring to the outside of said wall. 100

3. An electrical furnace including the combination of a wall having a hole therein, a heating resistance bar arranged in said furnace with an 110

end registering with said hole, a terminal bar loosely arranged in said hole to engage the end of said resistance bar and having an externally projecting shouldered end, a bellows having an inwardly extending end which engages the shouldered end of said terminal bar, a nut screw-threaded onto said terminal bar and clamping the inwardly extending end of said bellows to

the shouldered end of this bar, a refractory and electrically insulating ring fixed to the other end of said bellows and extending outwardly a sufficient distance to engage the outside of said wall around said hole, and an annular mounting member constructed and arranged to releasably clamp said ring to the outside of said wall.

JOHN T. NICHOLS.
